[57] **CLAIM**

The ornamental design for a monitor television receiver with disk player, as shown and described.

DESCRIPTION

FIG. 1 is a front, top and right side perspective view of a monitor television receiver with disk player showing our new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof;

FIG. 7 is a bottom plan view thereof;

FIG. 8 is a perspective view thereof similar to FIG. 1 with a front portion partially removed to expose a disk player in a retracted position;

FIG. 9 is a perspective view thereof similar to FIG. 8 with a disk player in an extended position; and,

FIG. 10 is a perspective view thereof similar to FIG. 8 with a handle in the extended position.

*FIG. 1**FIG. 2**FIG. 3**FIG. 4**FIG. 5**FIG. 6**FIG. 7**FIG. 8*

FIG. 9

FIG. 10
